UNITED STATES PATENT OFFICE.

LOUIE F. SMITH, OF SOUTH HOUSTON, TEXAS, ASSIGNOR OF ONE-HALF TO I. W. CLARK, OF SOUTH HOUSTON, TEXAS; ONE-FOURTH TO GEORGE D. COLLINS, THREE-SIXTEENTHS TO JAMES A. HENSON, AND ONE-SIXTEENTH TO MYRON COLLINS, ALL OF HARRIS COUNTY, TEXAS.

PUMP.

Application filed February 19, 1921, Serial No. 446,429. Renewed June 15, 1925.

To all whom it may concern:

Be it known that I, LOUIE F. SMITH, a citizen of the United States, residing at South Houston, in the county of Harris and State of Texas, have invented certain new and useful Improvements in a Pump, of which the following is a specification.

This invention relates to new and useful improvements in a pump.

One object of the invention is to provide a pump of the character described embodying a casing, a driving shaft which is eccentric thereto, and on which an impeller blade housing is splined, said housing carrying impeller blades which sweep around the walls of the fluid chamber within the casing and draw in the fluid through the intake port and drive it out through the discharge outlet.

Another object is to provide a pump of very simple construction, so that it may be cheaply and easily manufactured and easily kept in repair.

With the above and other objects in view the invention has particular relation to certain novel features of construction, operation and arrangement of parts, an example of which is given in this specification and illustrated in the accompanying drawings, wherein:—

Figure 1 is a vertical sectional view of the pump, and

Figure 2 is a transverse sectional view, and

Figures 3 and 4 show end and sectional view, respectively, of a housing employed.

In the drawings, the numeral 1 designates a pump casing having the intake 2 and the discharge 3. The casing is formed with a fluid chamber 4 which is closed by the removable end plate 5. The other end of the casing is formed with a long eccentric bearing 6, wherein the drive shaft rotates. Within the chamber 4 there is a circular housing 8 splined on the inner end of the shaft 7.

One end of this housing is formed of a circular plate which has an annular groove 9 cut in its outer face provided to receive an annular rib 10 formed on the inner face of the adjacent end of the casing 1. The inner face of the end plate 5 is formed with an inwardly projecting central bearing 11 provided with an eccentric socket aligned with the shaft 7 and into which the inner end of

said shaft fits. Surrounding the bearing 11 are adjacent rings 12 and 13, to which the opposing impeller blades 14 and 15, respectively, are pivoted. These blades work radially through opposing slots 16 and 17 in the housing 8. The outer edges of these blades are grooved lengthwise, said grooves continuing along the ends of the blades, and fitted into said grooves are the two-ply packing elements 18 and 19, preferably formed of soft metal or composition material so as to form a close fit with the chamber walls but will not scar or unnecessarily wear said walls. The housing being eccentric in the chamber 4 will form a crescent shaped fluid chamber, as shown in Figure 2 and as said housing rotates with the shaft 7 and around the bearing 11 the rings 12 and 13 will also rotate around the bearing 11 and carry the impeller blades 14 and 15 around the fluid chamber. As these blades sweep around through said chamber in close contact with the walls thereof a vacuum will be formed behind each blade which will cause the inflow of fluid through the intake 2 and the fluid in front of the blades will at the same time be forced out through the discharge 3. The end of the housing adjacent the end plate 5 is grooved to receive packing elements 20, 20 which form a close fit against said end plate to prevent the passage of fluid to the interior of the housing.

What I claim is:—

1. A pump including a casing having an intake and discharge, a removable end plate forming one end of the casing and forming within the casing a fluid chamber, a long eccentric bearing in the other end of said casing, a shaft rotatable in said bearing, a circular housing fixed on said shaft within the casing and being provided with opposing slots, a circular plate formed with an annular groove in its outer face forming one end of said housing, an annular rib formed on the inner face of the adjacent end of the casing and fitting in said groove, an inwardly projecting central bearing carried by the removable end plate of the casing and formed with an eccentric socket into which the inner end of said shaft fits, opposing adjacent rings surrounding said inwardly projecting bearing, opposing impeller blades pivoted to the respective rings and working

radially through the slots of the housing, and means carried by the outer edges of the blades for forming a water tight joint.

2. A pump including a casing having an intake and a discharge, a removable end plate forming one end of the casing and forming within the casing a fluid chamber, a long eccentric bearing in the other end of said casing, a shaft rotatable in said bearing, a circular housing fixed on said shaft within the casing and being provided with opposing slots, a circular plate formed with an annular groove in its outer face forming one end of said housing, an annular rib 10 formed on the inner face of the adjacent end of the casing and fitting in said groove, an inwardly projecting central bearing carried by the removable end plate of the casing and formed with an eccentric socket into

which the inner end of said shaft fits, adjacent opposing rings surrounding said inwardly projecting bearing, opposing impeller blades pivoted to the respective rings and working radially through the slots of the housing, the outer edges of said blades being provided with lengthwise grooves which continue along the ends of the blades, packing in said grooves in the outer edges of said blades forming a close fit with the chamber walls.

30

In testimony whereof I have signed my name to this specification in the presence of two subscribing witnesses.

LOUIE F. SMITH.
